UNITED STATES PATENT OFFICE.

WILLIAM S. MONROE, OF CHICAGO, ILLINOIS, ASSIGNOR TO THE BABCOCK & WILCOX COMPANY, OF BAYONNE, NEW JERSEY, A CORPORATION OF NEW JERSEY.

STEAM BOILER.

Application filed August 16, 1923. Serial No. 657,672.

In certain types of boilers having horizontally inclined water tubes, the tubes are arranged in separated banks, in order to provide a gas passage between the headers of the upper and lower banks through which the furnace gases may flow and giving a good location for a superheater. In this type of boiler, furthermore, it is often convenient to employ inclined headers, this arrangement permitting the water tubes to enter the headers normally. Where such inclined headers are used, the weight of the water tubes, particularly that of the lower bank, exerts a considerable cross strain and bending moment upon those portions of the headers connecting the banks of water tubes, and it is desirable to provide means to resist this bending and cross strain while, at the same time, permitting access to the superheater for the removal and replacement of tubes therein and the like.

My invention will best be understood by reference to the accompanying drawing, in which Fig. 1 is an elevational view, partly in section, of an illustrative embodiment of my invention applied to one type of boiler; Fig. 2 is a fragmentary view of Fig. 1 as seen from the left.

In this illustrative embodiment, the horizontally inclined water tubes are divided into an upper bank 10 and a lower bank 11, as shown, the two being spaced to form a superheater chamber in which is a superheater having tubes 12 which are connected to headers 13 and 14. A baffle 15 extends across the superheater chamber and across the upper bank of water tubes, so that the furnace gases pass across the lower bank of tubes, then over the superheater surface and then over one end of the upper bank, turning over the top of baffle 15 to pass downwards across the other end of the upper bank of tubes, and out between the headers of the upper and lower banks of tubes to the gas outlet.

In the illustrative embodiment, the banks of water tubes 10 and 11 are connected to headers nippled together, the headers being inclined and at right-angles to the water tubes, the upper ends of the headers being connected, as usual in this type of boiler, to a steam and water drum, not shown. It will be noted that, in a boiler of this type, gravity tends to swing the tubes and headers to the right of Fig. 1 and this must be re-

sisted by the headers and their connections. Where the headers are connected by long nipples, the nipples may not have sufficient resistance to cross strain and bending.

In the illustrative embodiment, I have provided nipples to give sufficient spaces through which the superheater tubes may be removed and at the same time, I have provided sufficient resistance to the cross strain and bending to which these nipples will be subjected, by extending some of the headers so that their connecting nipples will be short.

In the illustrative embodiment, long nipples are used for connecting the upper and lower parts of the down-take headers, since there is a gas outlet at the downtake end. The headers 16, 17 are connected by long nipples 18 only.

At the uptake end of the illustrative embodiment, the headers 19 and 20 are of normal length; that is, are only as long as the height of the respective banks. These normal length headers are connected by long nipples 21 and, since these nipples are smaller in diameter than the width of the headers, there will be spaces between the nipples.

The stiffening against bending is obtained in the illustrative embodiment by extending every third header 20' of the lower bank until it nearly reaches the corresponding header 19 of the upper bank. A short nipple 21' connects the long header to its upper header.

If desired, the spaces between nipples 21 may be closed by removable plates 22 held to the nipples by U-fastenings 23.

The long headers 20' give added resistance to bending and yet, by reason of the presence of the long nipples 21, access to the space between the banks for removing the superheater tubes is provided. Any one of the superheater tubes 12 may be withdrawn and replaced, the space between a pair of the nipples being sufficient for this purpose. If a superheater tube does not come opposite such a space, then it will be swung sideways until it does. The maximum amount of such sidewise motion required in the illustrative embodiment will be about one and one-half times the width of a header.

It will be obvious that the embodiment of my invention may be widely varied. For instance, while I have shown the headers 20' connected to the upper headers by the nip-

ples. 21', it is obvious that the nipple would not be required if these two headers were formed as one piece.

I claim:

5. 1. A superheater boiler having horizontally inclined water tubes arranged in separated upper and lower banks, a superheater between the banks with tubes extending lengthwise of the water tubes, headers connecting the ends of the water tubes in each bank and extending at right-angles to the water tubes, and connections between the uptake headers and other connections between the downtake headers of the two banks, some 10 of the headers at one end of the banks being spaced apart and being long enough to extend substantially across the space between the banks and the other headers at such end being disposed in the spaces between the first 15 named headers and being connected by long nipples.
2. A superheater boiler having horizontally inclined water tubes arranged in separated upper and lower banks, a superheater between the banks with tubes extending lengthwise of the water tubes, headers connecting the ends of the water tubes in each bank and extending at right-angles to the water tubes, and connections between the 20 uptake headers and other connections between the downtake headers of the two banks, every third header at one end of the banks extending substantially across the space between the banks and the remaining 25 connections at said end being formed of long nipples.
3. A superheater boiler having horizontally inclined water tubes arranged in separated upper and lower banks, a superheater between the banks with tubes extending lengthwise of the water tubes, and headers connecting the ends of the water tubes in each bank and extending at right-angles to the water tubes, pairs of adjacent headers at one end of the banks being connected by 30 long nipples and the headers between said pairs being substantially continuous across the space between said banks.
4. A superheater boiler having horizontally inclined water tubes arranged in separated upper and lower banks, a superheater between the banks with tubes extending lengthwise of the water tubes, headers connecting the ends of the water tubes in each bank and extending at right-angles to the water tubes, and connections between the uptake headers and other connections between the 40 downtake headers of the two banks, the connections at one end of the banks being formed by long nipples to provide a gas passage between the headers, baffling to direct the gases back and forth across the water tubes to the gas outlet, and the connections at the other end being formed partly of

long nipples and partly of headers disposed 65 between certain of said nipples and extending substantially across the space between the banks whereby spaces are provided through which the superheater tubes may be withdrawn.

5. A superheater boiler having horizontally inclined water tubes arranged in separated upper and lower banks, a superheater between the banks with tubes extending lengthwise of the water tubes, headers connecting the ends of the water tubes in each bank and extending at right-angles to the water tubes, and connections between the uptake headers and other connections between the 70 downtake headers of the two banks, the connections at one end of the banks being formed by long nipples to provide a gas passage between the headers, baffling to direct the gases back and forth across the water tubes to the gas outlet, and the connections at the other end being formed partly of a plurality of pairs of adjacent long nipples and partly of headers disposed between said pairs and extending substantially across the space between the 75 banks whereby spaces are provided through which the superheater tubes may be withdrawn.

6. A superheater boiler having water tubes arranged in separated banks, a superheater between the banks with tubes extending lengthwise of the water tubes, headers connecting the ends of the tubes in each bank, some of the headers at one end of the banks being spaced apart and connected by long nipples, and the others being disposed between said spaced headers and being substantially continuous across the space between the banks.

7. A superheater boiler having water tubes arranged in separated banks, a superheater between the banks with tubes extending lengthwise of the water tubes, headers connecting the ends of the tubes in each bank, pairs of adjacent headers at one end of the banks being connected by long nipples, and the headers between said pairs being substantially continuous across the space between said banks.

8. A superheater boiler having water tubes arranged in separated banks, a superheater between the banks with tubes extending lengthwise of the water tubes, headers connecting the ends of the tubes in each bank, and connections between the headers at one end of the banks, said connections being inclined to the vertical and some of them consisting of long nipples and others being interposed between the nipples and consisting of headers extending substantially across the space between the banks.
